UNITED STATES PATENT OFFICE.

MAURICE SWITZER, OF NEW YORK, N. Y., ASSIGNOR TO THE HAVANA-AMERICAN COMPANY, OF JERSEY CITY, NEW JERSEY.

DESIGN FOR A CIGAR-BOX.

SPECIFICATION forming part of Design No. 33,541, dated November 13, 1900.

Application filed October 5, 1900. Serial No. 32,190. Term of patent 3½ years.

To all whom it may concern:

Be it known that I, MAURICE SWITZER, a citizen of the United States, residing at New York, in the county of New York and State of New York, have invented and produced a new and original Design for Cigar-Boxes, of which the following is a specification.

My invention relates to a new and original design for cigar-boxes and is illustrated in the accompanying drawings, in which—

Figure 1 is a side elevation looking at one side of the box. Fig. 2 is a similar view looking at the other side. Fig. 3 is a front view, Fig. 4 a bottom view, and Fig. 5 an end view, of the box.

The leading features of my design consist in a cigar-box which is oblong in shape and the sides of which are ornamented by labels and which has a line of separation extending entirely therearound near one side thereof and at one side of and adjacent the line of separation a handle which is cylindrical throughout and the ends of which enter the front wall of the box at separated points, the front wall of the box being embellished intermediate the ends of the handle by an ornamental plate having a forwardly-projecting lug and opposite said plate and separated therefrom by the line of separation hereinbefore referred to by a similar ornamental plate, from which extends an ornamental arm spanning the line of separation and inclosing the lug, the box also being provided with tapes running from points about along the longitudinal median line of the sides of the box forwardly or toward the front thereof, the ends of the tapes being loose and those secured at one side of the box having buckles, while those secured at the other side of said box are formed with a series of holes and a rectangular plate provided with a loop at one end, which surrounds the loose end of one of the tapes.

In the said drawings the reference-numeral 45 1 designates the cigar-box, which, as shown, is

oblong in shape and on its sides 2 3 is ornamented by labels 4 5. The box has a line of separation 6 extending entirely therearound and near the side 3 thereof. Adjacent to and at one side of the line of separation 6 at the front 7 of the box is a handle 8, which is cylindrical throughout its extent and the ends of which enter the front wall 7 of the box at separated points 9 10. The front wall of the box is embellished intermediate the ends of the handle by an ornamental plate 11, having a forwardly-projecting lug 12, and opposite said plate and separated therefrom by the line of separation 6, hereinbefore referred to, is embellished by a similar ornamental plate 13, from which extends an ornamental arm 14, spanning the line of separation and having a circular orifice inclosing the lug. The box is also provided with tapes 15 and 16, which run or extend from points 17 about along the longitudinal median line of the sides of the box forwardly or toward the front thereof. The ends of the tapes are loose, and those numbered 15, secured to one side of the box, are formed with buckles at their loose ends, while those numbered 16, secured to the other side of the box are formed with a series of holes.

18 indicates a rectangular plate having at one end a loop 19, which surrounds the loose end of one of the tapes.

My design presents a cigar-box of novel, pleasing, and distinguished appearance.

Having thus described my invention, what I claim, and desire to secure by Letters Patent, is—

The design for a cigar-box as herein shown and described.

In testimony whereof I have hereunto set my hand in presence of two subscribing witnesses.

MAURICE SWITZER.
